Inventor:

J. K. Farley, Jr.

By Chamberlin & Brendenreid, Atty.

UNITED STATES PATENT OFFICE.

JESSE K. FARLEY, JR., OF KENILWORTH, ILLINOIS.

BOX FOR CANDY OR THE LIKE.

Application filed September 30, 1921. Serial No. 504,517.

To all whom it may concern:

Be it known that I, JESSE K. FARLEY, JR., a citizen of the United States, residing at Kenilworth, county of Cook, State of Illinois, have invented a certain new and useful Improvement in Boxes for Candy or the like, and declare the following to be a full, clear, and exact description of the same, such as will enable others skilled in the art 5 to which it pertains to make and use the same, reference being had to the accompanying drawings, which form a part of this specification.

My invention has for its object to produce 10 a simple and novel box or container having a cover which, after it has served its purpose as a closure for the box or container, becomes a complete article useful for other purposes. The cover may be any useful or ornamental article which would ordinarily be purchased by itself. The cover is preferably 15 an article which will serve to ornament or add to the appearance of the box or container as, for example, a completely framed picture which will give an ornamental effect to the top of the box or container and, when removed to expose the contents of the box, may be hung on the wall or placed elsewhere in the manner of an ordinary picture.

20 The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a perspective view of a candy box constructed and arranged in accordance 25 with the present invention;

Fig. 2 is a perspective view of the cover detached from the box;

Fig. 3 is a perspective view of the tray on which the cover rests when forming a closure for the box;

Fig. 4 is a perspective view of the box before the tray and cover are applied; and

Fig. 5 is a cross section through the closed box taken approximately on line 5-5 of 30 Fig. 1.

Referring to the drawing, A represents a box of any size or shape and made of any suitable material, and open at the top. B is a cover adapted to fit into the open top of the box; the cover being, in the arrangement

shown, in the form of a picture, 1, held between a back 2 and a glass 3, by means of a suitable frame 4, preferably of the passe partout variety.

In order to keep the cover from entering 60 too far into the box, it is necessary that some means be provided for supporting the cover, preferably flush with the upper edges of the box. In the arrangement shown, this means consists of a tray C which, in its simplest form, is simply a frame fitting into the box and having its walls slightly shallower than the walls of the box. At least some of the sides of the tray are provided with leaves or 65 wings 5, preferably of lace paper which may be folded inwardly over the contents of the box.

In using my improved device, the tray is set into the box or container which is then 70 filled with the candy or other goods; the leaves or wings 5 are folded inwardly over the goods, and the cover is then placed on top of the box, being supported by the upper edge of the tray. The parts are then fastened together, conveniently by means of a 75 ribbon 6 tied around the same.

It will be seen that the completed package 80 may be an extremely attractive one but that the purchaser of the package, instead of throwing away an expensive box which 85 would ordinarily be useless to him, may retain the cover and make it serve a purpose that would ordinarily be served by an article independently purchased.

The cover may be provided with suitable 90 means for supporting it after it has been removed from the box. In the arrangement shown, the cover is provided on the back or underside with a ring 7 by means of which 95 it may be hung on the wall.

As heretofore stated, the box and the tray 100 may be made of any suitable material, but I have found that my invention is well adapted for application to boxes made of cardboard in which case the tray also will usually be 105 made of cardboard.

While I have illustrated and described 110 with particularity only a single preferred form of my invention, I do not desire to be limited to the exact structural details thus illustrated and described; but intend to cover all forms and arrangements which come within the terms employed in the definitions of my invention constituting the appended claims.

I claim:

1. In combination, a box open at the top, a tray arranged loosely in the box and resting on the bottom thereof, the tray being slightly shallower than the box, and a cover in the form of a framed picture fitting loosely into the top of the box and resting on the tray.
  2. In combination, a box open at the top, a tray arranged loosely in the box and resting on the bottom thereof, the tray being slightly shallower than the box, a cover in the form of a framed picture fitting loosely into the top of the box and resting on the tray, and wings at the upper edges of the tray adapted to be folded inwardly over the contents of the box before the cover is placed in position.
  3. In combination, a box open at the top, said box having an upwardly directed shoulder extending around the interior
- thereof a short distance below the upper edge, and a cover in the form of a framed picture fitting loosely into the top of the box and resting on said shoulder, the thickness 25 of the cover being such that the upper surface lies approximately in the plane of the upper edges of the side walls of the box.
4. In combination, a box open at the top, a tray fitting loosely in the box and resting 30 on the bottom thereof, the tray being slightly shallower than the box, a cover in the form of a framed picture fitting loosely into the top of the box and resting on the tray, and a ribbon extending around the box and across the cover to hold the cover in place and permit it to be completely removed upon the untying of the ribbon.

In testimony whereof, I sign this specification.

JESSE K. FARLEY, JR.
